COLLAPSIBLE FURNITURE

Raymond W. Boucher, Dothan, Ala., assignor to
 Hedstrom Union Company, Fitchburg, Mass., a
 corporation of Massachusetts

Application December 15, 1953, Serial No. 398,328

5 Claims. (Cl. 155—143)

1

This invention relates to improvements in collapsible furniture. More particularly it provides improved collapsible frame structures designed to removably receive flexible sheet elements which, in conjunction with the frame structures, are adapted to serve as chairs, stools, or other items of furniture.

Heretofore, chair frames have been manufactured by suitably bending and shaping a single relatively long and substantially rigid metallic rod, with lower bends serving as feet, and with upper bends located and adapted to engage within pockets formed in a sheet element for supporting the sheet element in spread relation on the frame. In the rod-shaping process, portions of the rod cross each other at front and back, and at each side of the frame, and the crossing portions have been rigidly connected together to provide needed rigidity. However, such frames occupy a relatively large space when in use and when stored, and they are extremely awkward and space-consuming when it becomes necessary to ship one or a number of the items from place to place. Shipping costs are unduly high, and it has been difficult and expensive to adequately protect the items against damage in the course of shipment.

It is among the objects of the invention to provide chair frames, and the like, of the mentioned general type, having needed rigidity and strength when set up for use but having the character of being readily collapsible for storing, shipping and handling purposes. According to the invention, each frame, whether a chair frame or the frame of a stool or other furniture item, comprises rod sections pivotally connected together at their ends with each rod section crossing an adjacent rod section but with the regions of said crossings shiftable by reason of pivoted section-connectors which serve also as abutment seats for adjacent portions of the cross rod sections when the frame is in spread open condition, the said pivotal connections of the ends of the rod sections, in conjunction with the said pivoted section-connectors, permitting convenient and efficient collapsing of the frame from its said spread open condition to a relatively compact condition.

Another object of the invention is to provide a readily collapsible chair frame, or the like, wherein a series of generally straight relatively rigid rod sections have their ends pivotally connected together with each rod section crossing another rod section, and with each pair of rod sections which cross each other connected together adjacent to the region of their crossing by

2

pivoted connectors which constitute abutment seats for crossing rod sections when the frame is in spread open condition, the pivotally connected end portions of the rod sections at one end of all of the rod sections constituting feet for resting on the floor, or other support, and the pivotally connected end portions of the rod sections at the other end of all of the rod sections constituting generally upstanding spaced frame portions for engaging in pockets of a flexible sheet element to support the sheet element in spread relation on the frame.

It is, moreover, my purpose and general object to improve upon prior bent rod chair frames, and the like, and more especially to provide readily collapsible frames for chairs, and comparable items of furniture, of the general type which are formed from relatively rigid rod stock, and which removably support flexible sheet seat elements and the like.

In the accompanying drawings:

Fig. 1 is a perspective view of a collapsible chair embodying the features of the invention;

Fig. 2 is a perspective view of the frame of the chair of Fig. 1 in a partially collapsed condition;

Fig. 3 is a fragmentary perspective view showing, on a larger scale, the locking toggle at the front of the chair frame of Figs. 1 and 2;

Fig. 4 is a fragmentary perspective view, on the scale of Fig. 3, showing a pivotal rod-section-connector which may be employed at opposite sides of the chair frame of Figs. 1 and 2;

Fig. 5 is a perspective view of a collapsible stool frame embodying features of the invention; and

Fig. 6 is a view of the under pocket side of a flexible sheet element adapted to be removably supported on the stool frame of Fig. 5.

Referring to the drawings, the so-called butterfly type of chair as represented in Fig. 1 has a flexible sheet element 10 of any suitably strong material removably supported in relatively loose, spread condition over the chair frame, the under side of the element 10 preferably being equipped with a conventional pocket 12 at each of the four corners of the element, within each of which a generally upstanding portion of the frame engages, only one of the pockets 12 being visible in Fig. 1.

The invention relates to the frame structure whereby the chair, or other comparable item of furniture, may be readily converted between spread open and collapsed conditions.

In the embodiment of Figs. 1-4, the illustrated

chair frame comprises four similar rod sections 14, 16, 18 and 20 and four similar longer rod sections 22, 24, 26 and 28. The lower end of rod section 16 is pivotally connected at 30 to the lower end of the longer rod section 22, and the lower end of rod section 16 is pivotally connected at 32 to the lower end of the longer rod section 24. The upper ends of rod sections 14, 16 are pivotally connected together at 34, and the upper ends of the longer rod sections 22, 24 are pivotally connected together at 36. In the same manner, the lower end of rod section 18 is pivotally connected at 38 to the lower end of the longer rod section 26, and the lower end of rod section 20 is pivotally connected at 40 to the lower end of the longer rod section 28. The upper ends of rod sections 18, 20 are pivotally connected together at 42, and the upper ends of the longer rod sections 26, 28 are pivotally connected together at 44.

In the assembled frame, each rod section extends across and substantially in contact with an adjacent rod section but it is a feature of importance that the portions of the rod sections which are disposed across each other are relatively movable to permit variation of the angular relation of the crossing rod sections. To this end, each pair of crossing rod elements are pivotally connected together relatively close to the region of crossing of the sections. Referring to Fig. 2, each rod section has a connector member rigid thereon and pivotally connected to an adjacent similar connector member. The connector member on rod section 15 is indicated at 14 pivotally connected at 15^a to the connector member 21 on rod section 20. The connector member 19 on rod section 18 is pivotally connected at 19^a to the connector member 23 on rod section 22. Connector member 17 on rod section 16 is pivotally connected at 17^a to connector member 29 on rod section 28, and connector members 25 and 27 on rod sections 24 and 26, respectively, are pivotally connected together at 25^a.

Each connecting member is formed with a projecting abutment having a grooved edge for seating a rod section when the frame is spread open as in Fig. 1. This is best seen in Figs. 3 and 4 wherein the connector members 15, 21 on rod section 14, 20 are shown located above the region of crossing of rod sections 14, 20, with the abutment grooves 15^b, 21^b at lower edge portions of the connector members so that rod section 14 seats in groove 21^b and rod section 20 seats in groove 15^b when the frame is fully spread.

The connector members 25, 27 on rod sections 24, 26, as seen in Fig. 4, are located below the region of crossing of rod sections 24, 26, which is true also of the connector members 17, 29 and 19, 23 at the opposite sides of the frame. Connected members 25, 27 have their abutment grooves 25^b, 27^b at upper edge portions thereof with groove 25^b in position to constitute a seat for rod section 26, and groove 27^b in position to constitute a seat for rod section 24 when the frame is fully spread.

Preferably, the pivotally connected lower ends of the rod sections are equipped with short cylinders 48 of rubber, or the like, to avoid marring of the floor when the chair, or comparable item, is used in-doors. Also, if desired, means may be provided for releasably maintaining the frame in its fully spread condition, such a means being indicated generally at 48, and shown in detail in Fig. 3, associated with the rod sections 14, 20 at the front of the chair frame. Toggle links 50, 52 are pivotally connected respectively to rod section 14 and rod section 20, are pivotally con-

nected together at 54, with an inverted U-channel element 56 at the connection 54. Hence, when the links 50, 52 are pressed downward into alignment, the element 56 stops the links in substantial alignment and the toggle maintains the frame fully spread until the toggle is broken preparatory to collapsing of the frame.

Ordinarily, the sheet element 10 will be removed before collapsing the frame.

Figs. 5 and 6 relate to a modification in the form of a collapsible stool in the frame of which all of the rod sections 58 may be identical in shape and length, and fewer in number than in the chair frame of Figs. 1-4. All of the pairs of connector members, indicated generally at 60, may be identical, with all of the pairs located below the regions of crossing of the rod sections generally similar to the connector members 25 and 27 of Fig. 4. The stool frame of Fig. 5 collapses generally in the same manner as the previously described chair frame.

A triangular shaped flexible sheet element 62, as shown in Fig. 6, has the corner pockets 64 at its under side, each adapted to engage over the upper pivotally connected end portions of a pair of rod sections, the same as described in connection with the sheet element 10 of Fig. 1.

The herein disclosed collapsible frame features may be embodied in various items of furniture, and it is intended that the patent shall cover, by suitable expression in the appended claims, whatever features of patentable novelty exist in the invention disclosed.

I claim as my invention:

1. A collapsible frame for an article of furniture, comprising a series of relatively rigid rods of which each rod is disposed in crossing relation to another rod to provide at least three pairs of crossing rods, the opposite ends of each rod being pivotally connected each to one end of a rod of a different pair of crossing rods thereby to provide at least three lower rod-end pivotal connections and at least three upper rod-end pivotal connections, connector means adjacent to the region of crossing of each said pair of crossing rods, each said connector means comprising two connector elements of which each is rigid on a different one of the crossing rods and the two connecting elements being pivotally connected together at a location spaced from the region of crossing of the rods on which said connector elements are rigid, the connector element on each crossing rod having a projecting abutment against which the adjacent crossing rod seats when the crossing rods are in a predetermined angular relation, with said lower rod-end pivotal connections adapted to rest on a support, and with said upper rod-end connections adapted to support a sheet element in spread relation to the frame.

2. A collapsible frame for an article of furniture, comprising a series of relatively rigid rods of which each rod is disposed in crossing relation to another rod to provide at least three pairs of crossing rods, the opposite ends of each rod being pivotally connected each to one end of a rod of a different pair of crossing rods thereby to provide at least three lower rod-end pivotal connections and at least three upper rod-end pivotal connections, connector means adjacent to the region of crossing of each said pair of crossing rods, each said connector means comprising a pair of pivotally connected ears of which one is rigid on each crossing rod adjacent to the region of crossing of the rods whereby the crossing rods are relatively movable about the pivot of the con-

necter elements, and abutment means on each connector element for stopping relative movement of the crossing rods with the rods of each pair of crossing rods in predetermined angular relation such that said lower rod-end pivotal connections constitute spaced feet for resting on a support, and said upper rod-end pivotal connections constitute spaced elevated supports upon which a spread sheet element may be removably mounted.

3. A collapsible frame for an article of furniture, comprising a series of relatively rigid rods of which the opposite ends of each rod each is pivotally connected to an end of a different rod, with each rod constituting, with another rod, a generally V-shaped portion of the frame, and with each rod constituting, with still another rod, a generally inverted V-shaped portion of the frame, whereby the lower rod-end pivotal connections of said V-shaped portions of the frame constitute spaced feet for resting on a support, and the upper rod-end pivotal connections of said inverted V-shaped portions of the frame constitute elevated spaced supports for a sheet element which may be spread over the frame, each said rod being disposed in crossing relation to another rod, and means adjacent to each region of said crossing of rods pivotally connecting together the crossing rods, each said pivotally connecting means having abutments thereon upon which said crossing rods seat when the crossing rods are in a predetermined angular relation.

4. A collapsible frame for an article of furniture, comprising a series of relatively rigid rods of which each rod is disposed in crossing relation to another rod to provide at least three pairs of crossing rods, the opposite ends of each rod being pivotally connected each to one end of a rod of a different pair of crossing rods thereby to provide at least three lower rod-end pivotal connections and at least three upper rod-end pivotal connections, connector means adjacent to the region of crossing of each said pair of crossing rods, each said connector means comprising two connector elements of which each is rigid on a different one of the crossing rods and the two connecting elements being pivotally connected together at a location spaced from the region of crossing of the rods on which said connector elements are rigid, the connector element on each crossing rod having a projecting abutment

against which the adjacent crossing rod seats when the crossing rods are in a predetermined angular relation, with said lower rod-end pivotal connections adapted to rest on a support, and with said upper rod-end connections adapted to support a sheet element in spread relation to the frame, and means associated with one of said pairs of crossing rods operative to releasably lock said crossing rods in their said predetermined angular relation.

5. In a collapsible chair and the like, a frame comprising at least three pairs of relatively rigid rods of which each rod has its opposite ends each pivotally connected to an end of another of said rods with some of the rod-end pivotal connections low down on the frame and constituting feet for resting on a support, and with an equal number of the rod-end pivotal connections at elevated locations on the frame for removably supporting a flexible sheet element in spread relation on the frame, each of said rods being disposed in crossing relation to another of said rods, a pair of pivotally connected connector elements adjacent the region of each crossing of rods with one element of each said pair rigid on each of the adjacent crossing rods whereby the crossing rods are relatively movable in closely adjacent parallel planes, each of said connector elements having a projecting abutment upon which one of the crossing rods seats when the crossing rods are in a predetermined angular relation, and a flexible sheet element having pockets at its underside whereby said sheet element may be removably spread upon the frame with each of said elevated rod-end pivotal connections engaged within a said pocket of the flexible sheet element.
